UNITED STATES PATENT OFFICE.

FRANK A. GOODNESS, OF MARION, INDIANA, ASSIGNOR OF ONE-HALF TO HERBERT E. KINNEAR, OF MARION, INDIANA.

OSCILLATING VALVE.

1,083,208.

Specification of Letters Patent.

Patented Dec. 30, 1913.

Application filed August 21, 1912. Serial No. 716,299.

To all whom it may concern:

Be it known that I, FRANK A. GOODNESS, a citizen of the United States, residing at Marion, in the county of Grant and State 5 of Indiana, have invented certain new and useful Improvements in Oscillating Valves, of which the following is a specification, reference being had to the accompanying drawings.

10 The present invention relates to new and useful improvements in valves and more particularly to a rotary oscillating valve which is designed to be used in conjunction with internal combustion engines.

15 The primary object of the present invention is to provide a valve of the character aforesaid which will be positive in operation and during the oscillation thereof, it will automatically clean the valve seat.

20 A further object of the present invention resides in constructing a valve casing for a valve of the aforesaid character, which may be mounted within the cylinder of the engine to form a more rigid construction to 25 resist the internal strains exerted owing to the explosions.

25 The invention has for a still further object a simple, durable and efficient construction of apparatus of this character, the parts 30 of which may be cheaply manufactured and readily assembled and installed, and which will require practically no attention to maintain in proper running order. And the invention also aims to generally improve 35 this class of devices and to render them more useful and commercially desirable.

35 In the accompanying drawings has been illustrated a simple and preferred form of the invention, it being, however, understood 40 that no limitation is necessarily made to the precise structural details therein exhibited, but that the right is reserved to any changes, alterations, and modifications to which recourse may be had within the scope of the 45 invention and without departing from the spirit or sacrificing the efficiency of the same.

45 In the said drawings, Figure 1 illustrates the side elevation of a cylinder having my invention applied thereto. Fig. 2 is a detail 50 section taken through the cylinder illustrating the valves. Fig. 3 is a horizontal section taken through one of the valve casings, Fig. 4 is a detail perspective view of one of the valves. Figs. 5 and 6 are detail trans-

verse sections taken on the lines 5—5 and 55 6—6 respectively of Fig. 4.

Reference now being had to the accompanying drawings wherein corresponding parts are designated by like numerals throughout the several views, the numeral 1 indicates an ordinary cylinder casing having the usual reciprocating piston 2 mounted therein. Mounted in the upper end of the cylinder 1 is a pair of parallel extending intake and exhaust valve casings 4 and 3, respectively, between which is formed an explosion chamber 5. Each of these valve casings is preferably mounted within the cylinder walls which will obviously provide a more rigid construction, said valve casings 70 being preferably of cylindrical form. The intake valve casing is provided with an intake port 6 and formed opposite from the said port 6 is an inlet port 7 leading from the valve casing 4 to the explosion chamber. 75 The exhaust valve casing 3 is provided with an exhaust port 8 leading from the explosion chamber 5 and an exhaust port 9 which is in communication with the exhaust manifold of the engine. Mounted within these 80 valve casings are rotary oscillating valves, each of which is mounted upon the shaft 10 and extends longitudinally of a casing. This shaft is journaled in bearing blocks 11 and 12, which are detachably mounted within opposite ends of the valve casing. Fixed to each of the shafts 10 are inwardly extending arms 13 which have pivotally connected to their free ends the valve actuating 85 rod 14. These valve rods 14 are operatively 90 mounted within guides 15 formed upon the outer periphery of the cylinder casing, and the rods have also mounted thereon coil springs 16 which normally hold the valves in a closed position. To operate these valve 95 rods so that the valves will be opened and closed at the desired intervals to complete the intake and discharge of the gases to the cylinder, I provide a pair of cams 17 and 18, respectively, upon the periphery of 100 which is adapted to ride the lower extremity of the valve rods 14. These cams 17 and 18 are each provided with gear wheels 19 which are in mesh with a gear wheel 20 keyed upon the crank shaft of the engine whereby upon 105 the rotation of the crank shaft, the cams will also be operated, which in turn will obviously operate the valves.

Each of the valves is provided with a tubular sleeve 21 which is keyed or in any other manner fixed upon the shaft 10, and this sleeve 21 has extending from the diametrically opposite sides thereof the arms 22 and the valve supporting arms 23, respectively. The arms 22 are integrally connected by a longitudinal guide bar 27. Slidably mounted upon the valve supporting arms 23 is a segmental valve blade 24. The apex of this valve blade 24 is provided with a longitudinally extending recess 25 for the reception of the arms 23 and the leaf spring 26, which is rigidly fixed at its medial portion to the sleeve 21. The outer or free ends of the leaf spring 26 are curved, and rest upon the inner face of the valve blade, thereby providing means for holding the blade in an extended position, for a purpose which will be hereinafter described. The outer face of the valve blade 24 is curved to conform to the configuration of the inner periphery of the valve casing, and the longitudinal edges thereof tapered to a point, as at 28, to form cutting edges, as shown. The outer face of the guide bar 27 is also curved to conform to the configuration of the inner periphery of the valve casing, so that upon the oscillation of the valve within the casing it will be allowed to operate.

It is obvious from the foregoing description, taken in connection with the accompanying drawings that the guide bars 27 of the valves each operate across the ports 7 and 8 leading from the valve chambers to the exhaust chamber and obviously clean the same to prevent the accumulation of any hydrocarbon or other foreign matter which should happen to accumulate therein. The valve blades 24 also operate across the ports 6 and 9 of the valve casing and the tapered edges thereof, indicated by the numeral 28, scrape along the inner periphery of the valve casing thereby also removing any hydrocarbon or foreign matter which should happen to accumulate thereon. It is apparent that the leaf spring 26 normally holds the valve blades in an extended position, thereby closing communication between the inlet and outlet ports and, as these valve blades are slidably mounted upon the arms 23, it is to be noted that upon the explosion within the cylinder, the internal strains thereof will be exerted upon the valve blades which however will effectually prevent any escape of the gases through the intake or exhaust ports.

Having thus described my invention, what is claimed is:—

1. A valve for internal combustion engines comprising a casing, an oscillatory shaft mounted therein, a valve blade movable with said shaft and radially movable with respect thereto, and means yieldingly

holding said valve blade in frictional engagement with the casing wall.

2. A valve for internal combustion engines comprising a casing, an oscillatory shaft mounted therein, supporting arms fixed upon the shaft, a valve blade radially movable upon the supporting arms, and means arranged between the supporting arms to yieldingly hold the valve blade in frictional engagement with the casing wall. 75

3. A valve for internal combustion engines comprising a casing, an oscillatory shaft mounted therein, a supporting member fixed upon said shaft, a valve blade mounted upon said member for radial movement, and means on said member yieldingly holding the valve blade in frictional engagement with the casing wall. 80

4. A valve for internal combustion engines comprising a casing, an oscillatory shaft mounted therein, a valve blade in the casing to oscillate with said shaft and radially movable with respect to said shaft, said blade having longitudinal scraping edges for engagement with the casing wall. 90

5. A valve for internal combustion engines comprising a casing, a shaft mounted in said casing, arms fixed upon said shaft, a valve blade having a longitudinal groove to receive said arms, said blade being radially movable upon the arms with respect to the shaft, and a spring bearing against the base wall of said groove to yieldingly hold the valve blade in frictional engagement with the casing wall. 100

6. A valve for internal combustion engines comprising a casing, a shaft mounted in said casing, a sleeve keyed upon the shaft, a valve blade mounted upon the sleeve for radial movement with respect to the shaft, 105 and a spring fixed to said sleeve and bearing against the valve blade to yieldingly hold the same in engagement with the casing wall.

7. A valve for internal combustion engines comprising a casing, a shaft mounted in said casing, a sleeve fixed upon the shaft and provided with a longitudinal arm for scraping engagement with the casing wall, a valve blade radially movable in the casing 115 with respect to the shaft and movable in the casing with said shaft, and a spring fixed upon the sleeve and bearing against the valve blade to yieldingly hold the same in contact with the casing wall. 120

8. A valve for internal combustion engines comprising a casing, a shaft mounted in said casing, a sleeve keyed upon said shaft and provided with a longitudinal arm for scraping engagement with the casing wall, 125 spaced radial arms projecting from the opposite side of the sleeve, a valve blade radially movable upon said arms, and a spring fixed to the sleeve between the arms and bearing against the valve blade to yield- 130

ingly hold the same in frictional engagement with the casing wall.

9. A valve for internal combustion engines comprising a casing, a shaft mounted in said casing, a sleeve fixed upon said shaft and provided with means located upon one side of the shaft for scraping engagement with the casing wall, a radially disposed arm projecting from the opposite side 10 of the shaft at each end of the sleeve, a valve blade provided with a groove to receive said

arms, and a spring fixed to the sleeve between the arms and bearing against the base wall of the groove to yieldingly hold the valve blade in frictional engagement with 15 the casing wall.

In testimony whereof I hereunto affix my signature in the presence of two witnesses.

FRANK A. GOODNESS.
